Specification of Letters Patent.

Patented Aug. 2, 1921.

Application filed August 29, 1919. Serial No. 320,631.

To all whom it may concern:

Be it known that ALTON B. HEIMBACH, citizen of the United States, residing at Duluth, in the county of St. Louis and State 5 of Minnesota, has invented certain new and useful Improvements in Wrenches, of which the following is a specification, reference being had therein to the accompanying drawing.

10 This invention relates to wrenches and has special reference to what may be termed a quickly adjustable wrench and of a type shown in my co-pending application Serial No. 296,190, filed May 10th, 1919; and former 15 Patent No. 1,142,426, dated June 8, 1915.

The principal object sought is to provide an improvement in the art.

Another object is to provide a wrench of this type which will not require manual effort to insure its hold upon an object being turned, such as a nut or the like.

Other objects and advantages of the novel structure will appear in the further description of the invention.

25 Referring to the accompanying drawings forming part of this application and in which like reference characters represent like parts:

Figure 1, is a side elevation of one of my 30 improved wrenches in normal position.

Fig. 2, is a similar view of the wrench showing its appearance when being adjusted.

Fig. 3, is a head end view of Fig. 1, and 35 Fig. 4, is a handle end view of same.

1 represents the main body portion or shank of the wrench, it having formed therein a central longitudinally extending slot indicated at 2 and which slot terminates 40 at both ends on an incline, such being illustrated at 3 and 4. The shank 1 has formed integral therewith a fixed jaw 5 and carries within the slot 2 therein a slidably movable jaw 6, said jaw 6 having a central extending portion 7 which fits within the slot 2 45 of the body portion. On either side of the slot 2 and upon the jaw side of the shank 1 are formed serrations or teeth indicated at 8 said teeth being inclined and pointed 50 toward the fixed jaw of the wrench. The slidable jaw is of the same width as the shank of the wrench which results in square shoulders thereupon on either side of the central portion 7 and these shoulders are 55 provided with inclined teeth for coöperative interlocking engagement with the teeth

upon the shank. It is evident from the fact that the teeth are inclined backwardly or away from the fixed jaw, that is, pointing toward the head end of the wrench, that 60 when the movable jaw 6 comes into locked engagement with the shank there is a slight backward movement thereof after the points of the coöperating teeth pass each other and when the wrench has engaged an object to 65 be turned intermediate of its jaws. When the slidable jaw is in such interlocked position and turning stress is applied to the wrench, it becomes impossible for the movable jaw to slip or release its engagement 70 with the shank, whereas, if the teeth were straight, as employed upon wrenches of somewhat like character such holding properties do not exist; thus the inclined teeth become an essential part of my present invention. 75 The fact that there is a slight separation of the jaws as the movable jaw comes into position is also considered a novel and advantageous feature in that the wrench will not stick to the object engaged and interfere with its quick removal.

The central portion 7 of the movable jaw 6 extends slightly above the back of the shank of the wrench and has rigidly fixed thereto, by means of suitable rivets indicated at 9, a spring handle 10 which extends backwardly substantially horizontally with the body portion of the wrench to a point approximately even with the rear end of the movable jaw where it becomes materially 85 reduced in thickness and is bent rather sharply back under itself and toward the back of the wrench extending to a point approximately midway its ends where it is turned at right angles, reduced in width 90 forming shoulders to rest upon the back of the wrench and extends within the slot 2 where it is thus guided in its longitudinal movement and supported against lateral thrust. This bent and reduced portion of 95 the movable jaw handle is suitably tempered and acts as a spring to hold the jaw normally in locked engagement with the shank of the wrench as shown in Fig. 1, and for any adjustment of the jaw 5 the spring end of the 100 handle 10 must be manually compressed as shown in Fig. 2 of the drawings, when the jaw 6 may be adjusted by sliding to any desired position within the predetermined limits thereof.

110 The handle 10 is preferably the full width of the body portion of the wrench and at its

point of contact with the extension 7 are formed shoulders indicated at 11-11, which bear upon the back of the wrench and which bearing point is a predetermined distance 5 forward of a straight line with the face of the movable jaw 6, the object of which is to wholly free the jaw 6 from engagement with the teeth on the shank of the wrench when the spring handle 10 is compressed as clearly 10 seen in Fig. 2 of the drawings. To further insure such clearance I omit three or four of the foremost teeth on the shoulders of the movable jaw, as there are ample others to insure positive holding of the jaw.

15 From the foregoing it is evident that I have materially simplified the adjusting mechanism of the wrench and that all that is necessary to accomplish such by the user, is to place the thumb of the hand which is 20 grasping the wrench, upon the spring handle of the movable jaw and slide it to any adjustment desired, when as soon as the pressure of the thumb is released the expansive energy of the spring handle 10 will bring 25 the jaw into locked position where it will remain against any pressure put thereupon.

due to the gripping inclination of the coöperatively engaging teeth, as above described.

Having thus described my invention, what I claim as new, and desire to secure by Letters Patent is:

The combination with a wrench comprising a shank having a jaw fixed thereto, a slot within the shank, a movable jaw adjustable through the slot from the back of the 35 shank, and coöperatively engageable teeth upon the shank and the movable jaw, of a bearing for said adjustable jaw spaced in advance of the working face thereof and a one-piece resilient member rigidly fixed to 40 the adjustable jaw, said resilient member being bent under and backwardly upon itself the free end thereof being engaged within the slot in the shank to prevent lateral movement thereof substantially as described. 45

In testimony whereof I hereunto affix my signature in the presence of two witnesses.

ALTON B. HEIMBACH.
